DESIGN FOR A RACK FOR KITCHEN UTENSILS OR THE LIKE

Horner H. Hopkins, Des Moines, Iowa, assignor to Cobbs-Hamilton Co., Des Moines, Iowa

Application October 27, 1939, Serial No. 87,995

Term of patent 7 years

To all whom it may concern:

Be it known that I, Horner H. Hopkins, a citizen of the United States and resident of Des Moines, Polk County, Iowa, have invented a new, original, and ornamental Design for a Rack for Kitchen Utensils or the like, of which the following is a specification, reference being had to the accompanying drawing, forming a part thereof.

Fig. 1 is a front elevational view of a rack for kitchen utensils or the like, showing my design.

Fig. 2 is a top elevational view; and

Fig. 3 is an end elevational view thereof.

I claim:

The ornamental design for a rack for kitchen utensils or the like, substantially as shown.

HORNER H. HOPKINS.
